[57] **CLAIM**

The ornamental design for a handheld data terminal enclosure, as shown and described.

DESCRIPTION

FIG. 1 is a top plan view of a handheld data terminal enclosure showing our new design;

FIG. 2 is a bottom plan view thereof;

FIG. 3 is a bottom end elevational view thereof;

FIG. 4 is a top end elevational view thereof;

FIG. 5 is a right side view thereof;

FIG. 6 is a left side view thereof; and,

FIG. 7 is a top bottom end and left side perspective view thereof.

The broken lines shown in FIGS. 1-7 are included for the purpose of illustrating functional elements only and form no part of the claimed design.
